UNITED STATES PATENT OFFICE.

JAMES M. GARNER AND CARVER C. CLARK, OF HOLT, ALABAMA.

BRICKMASON'S TOOL.

Application filed April 17, 1922. Serial No. 553,703.

To all whom it may concern:

Be it known that we, JAMES M. GARNER and CARVER C. CLARK, citizens of the United States of America, residing at Holt, in the 5 county of Tuscaloosa and State of Alabama, have invented certain new and useful Improvements in Brickmasons' Tools, of which the following is a specification.

Our invention relates to a brickmason's 10 tool used for finishing joints in tapestry brick, cut stone and the like.

With this tool we propose to furnish the brickmason with a simple yet efficient device that will cut mortar joints to any desired 15 depth and trowel same in one operation. The device, provided with rollers or wheels, thereby reducing friction and labor to a minimum, is designed for the interchange of cutting and troweling tools for 20 various widths and shapes of joints as well as the feature of adjustability as to depth of joint.

These and other objects and advantages will more fully appear as the nature of the 25 invention is more clearly understood from the following specification, the subject matter of the claim and the views illustrated in the accompanying drawings, in which:—

Figs. 1 and 2 are respectively side elevation 30 and top plan views of our improved brickmason tool.

Figs. 3 and 4 illustrate some of the different tools adapted to be used with this tool.

Referring to the drawings, wherein similar 35 reference numerals refer to similar parts throughout the several views, 1 denotes the U-shaped frame of the device with an end extension socket 2 for the attachment of 40 the handle 3 with ferrule 4 securing handle to said frame. We propose to journal the wheels 5 to the frame 1 by means of the axles 6 extending from side to side and through the frame. Midway between the 45 axles 6 is a cross frame or brace 7 with a vertical socket 8 for the reception of shanks 9 and 10 of tools to be used in connection with this device. The tools are secured in this socket by the set screw 11 50 which also permits of the raising or lowering of said tools for any desired depth of mortar joint. The design of the tools 12

and 13 shown in the drawings has on the tool 12 a scraping face 14 which gouges the mortar out of the joints to a uniform depth, 55 while the tool 13 trowels the joint with its inclined face 15, thereby forming a smooth uniformly deep joint so desired by all builders. Tools 12^a and 13^a show wider types of the tools 12 and 13, their shanks 9 60 and 10 being adapted to be clamped in the socket 8.

In operation, the shanks of the tools corresponding to the width of the joints desired are inserted into the socket 8 and after an adjustment as to depth are secured in said socket by the set screw 11. The handle is grasped by the operator, and the tool is moved along the joints both vertically and horizontally, cutting the mortar 70 away, leaving a clean trowelled joint neatly done, and in half the time required for the use of the two tools separately.

Though we have described with great particularity the details of the embodiment 75 of the invention herein shown, it is not to be construed that we are limited thereto as changes in arrangement and substitution of equivalents may be made by those skilled in the art without departing from the invention as defined in the appended claim.

Having thus described our invention, what we claim as new and desire to secure by Letters Patent, is:—

A device of the character described, comprising a frame having at one end a handle, a pair of wheels mounted on each side of the frame, a cross member connecting the sides of the frame substantially midway between the front and rear pair of wheels, a 90 socket on said cross member set at right angles to the frame, interchangeable mortar cutting and trowelling tools having elongated angled shanks adapted to be received in said socket, and means to clamp said shanks in desired adjusted position in the socket.

In testimony whereof we affix our signatures.

JAMES M. GARNER.
CARVER C. CLARK,

Witness:

J. M. KICKER.
